FRONT PANEL UNIT FOR A VEHICLE

Jesse R. Birchard, Walled Lake, Mich., Albert D. Mortrude, Pompano Beach, Fla., and Ray C. Conner, Battle Creek, Mich., assignors, by mesne assignments, to The Cortez Corporation, Kent, Ohio, a corporation of Ohio

Filed Sept. 20, 1968, Ser. No. 13,621

Term of patent 14 years

Int. Cl. D12—14

U.S. Cl. D14—6

FIG. 1

FIG. 2

FIG. 3

FIG. 4

FIG. 5

FIG. 6

FIG. 1 is a front left quarter perspective view of a front panel unit for a vehicle embodying our new design; FIG. 2 is a front elevational view thereof;

FIG. 3 is a partial side elevational view thereof;

FIG. 4 is a right front quarter perspective view of a modified form thereof;

FIG. 5 is a front elevational view thereof;

FIG. 6 is a partial right side elevational view thereof.

The portion in broken lines is shown for illustrative purposes only.

We claim:

The ornamental design for a front panel unit for a vehicle, as shown and described.
